CLAIM

The ornamental design for a cartridge for a vaping device, as shown and described.

DESCRIPTION

FIG. 1 is a perspective view of a new design for a cartridge of a vaping device.

FIG. 2 is a front view of the cartridge for a vaping device of FIG. 1.

FIG. 3 is a back view of the cartridge for a vaping device of FIG. 1.

FIG. 4 is a left side view of the cartridge for a vaping device of FIG. 1.

FIG. 5 is a right view of the cartridge for a vaping device of FIG. 1.

FIG. 6 is a top view of the cartridge for a vaping device of FIG. 1; and,

FIG. 7 is a bottom view of the cartridge for a vaping device of FIG. 1.

Broken lines in the drawings depict features of the cartridge for a vaping device that form no part of the claimed design.

1 Claim, 6 Drawing Sheets
